Des. 179,866
Patented Mar. 12, 1957

179,866

LAUNDRY BAG OR THE LIKE

Phyllis F. Sork, Philadelphia, Pa.

Application February 14, 1956, Serial No. 40,161

Term of patent 3½ years

(Cl. D58—2)

I claim:

The ornamental design for a laundry bag or the like, substantially as shown.
